UNITED STATES PATENT OFFICE.

GEORGE W. FOSTER, OF LOWELL, MASSACHUSETTS.

TRAVERSE MECHANISM FOR WINDING-MACHINES, &c.

1,075,286.

Specification of Letters Patent.

Patented Oct. 7, 1913.

Application filed May 19, 1909. Serial No. 496,971.

To all whom it may concern:

Be it known that I, GEORGE W. FOSTER, a citizen of the United States, residing at Lowell, in the county of Middlesex, State of Massachusetts, have invented a certain new and useful Improvement in Traverse Mechanisms for Winding-Machines, &c., of which the following is a specification, reference being had therein to the accompanying drawings.

The invention consists in a novel and improved traverse mechanism adapted to be employed for actuating the traverse-devices of machines for winding yarn, thread, and cord, and in other similar connections. It is in the nature of an improvement upon the traverse mechanism of United States Letters Patent No. 789,601, granted to me under date of May 9, 1905, for winding machine. A characteristic feature of the mechanism of the said patent is a modified crank-motion by which the wrist-pin from which the traverse-devices are actuated has given thereto a continuous forward movement, with gradual acceleration of speed as the winding-guide approaches the end of its traversing movement in either direction,—so as to cause a quick reversal of the traversing movement and produce a sharp bend of the yarn, or other material being wound, at each end of the helices of the cop,—and with gradual retardation of speed as the winding-guide travels from an end of the traversing movement toward the middle of the length of the cop. The said crank motion occasions, incidentally, a slight shifting of the wrist-pin inward and outward with relation to the center of rotation, the path of movement of the wrist-pin remaining approximately circular, however.

The improved traverse mechanism in which my present invention resides is constructed to cause quick reversals of the movement of the winding-guide at the end of its traverse in either direction, and, in addition, to cause the winding-guide to travel equal or approximately equal distances in equal times in moving from substantially one end of the traverse to substantially the other end thereof, without retardation in approaching either end, in order thereby to insure that the wound mass shall be straight longitudinally at the surface thereof, and not concaved or hollowed intermediate the ends of the helices, as occurs when

the traveling movement of the winding-guide is fastest between the two extremes of the traverse, which usually is the case when the motion of the winding-guide is derived from a rotating crank.

The present invention employs, as in the case of the prior mechanism, two cranks of different radii rotating concentrically in opposite directions, and a wrist-pin carrier. In the prior mechanism the said carrier is hung to the outer crank and in sliding engagement with the inner crank. In my present invention the wrist-pin carrier is hung pivotally upon the crank of less radius, and is in sliding engagement with that of greater radius. By this means I cause it to have a bodily movement of considerable extent in the direction of its own length upon the latter crank, the effect of which is to cause the wrist-pin to move inward to a material extent in certain portions of the revolutions of the cranks, so as to travel in a narrow elongated path or orbit, the longitudinal axis of which is the straight line connecting those opposite positions of the wrist-pin that correspond with the respective ends of the traverse of the winding-guide. The sides of the said path or orbit bend inward toward the said axis, and may even cross it and each other when the parts are properly proportioned to secure such result in the working.

In winding yarn, thread, etc., with a quick traverse and a friction-drive, there is a tendency, at certain stages in the increase in diameter of the wound mass, for a number of courses to accumulate one immediately over or closely adjacent another in bands, forming ridges and also rendering the ends of the wound mass defective. The aim of the second portion of my invention is to obviate this drawback. This portion of the invention consists in improved means of changing the lay of the yarn, etc., in being wound, so as to separate the coils of each course from those of the preceding course sufficiently to avoid the production of bands and ridges. To this end I provide devices for setting the winding-guide forward or back slightly so as to pass the same point earlier or later, as the case may be, in successive traverses. In the illustrated embodiment of the invention I construct the outer crank as a permitting-crank which changes position so as to occasion a relative shift of

the winding-guide forward or rearward. This shift is slight in amount, but sufficient to effect a displacement of the helices which are in course of being wound far enough 5 with relation to those last previously wound to prevent the coils of the former from exactly overlying the coils of the latter. As one specific means of producing the desired action I provide the pin of the said 10 outer crank with an eccentric mounting in the rotating carrier thereof, and provide for a turning movement of the said mounting. One specific construction of the said eccentric mounting consists in a journal-portion 15 provided in connection with the crank-pin, eccentrically related to the latter, and fitted to a bearing in connection with the rotating carrier.

An embodiment of the invention is illustrated in the drawings, in which latter,—

Figure 1 is an elevation of a portion of a winding frame having the said embodiment of the invention applied thereto. Fig. 2 is a sectional view of the said embodiment, on an enlarged scale. Fig. 3 is a front elevation of the wrist-pin-carrier, detached. Fig. 4 is a back elevation thereof. Fig. 5 is an end view thereof. Fig. 6 is a diagram illustrating the working of the devices of Figs. 1 to 5. Fig. 7 is a sectional view of a modified embodiment of the invention. Fig. 8 is a diagram illustrating the working of the said modified embodiment.

The drawings show only enough of the usual parts of a winding machine to render clear the relations and application of the embodiment, aforesaid, of the invention.

Having reference to the drawings,—at 1, Fig. 1, is a fixed rail, extending lengthwise of the machine. The said machine is of the type in which the yarn, thread, or other material, is wound upon shells or other receivers or cores through the frictional engagement between the surface of a shell or the like, or of the wound mass thereon, and that of a driver-roll with which such surface makes contact. A driver-roll is shown at 2 fixed upon a spindle 3 extending transversely of the machine and mounted in bearings provided therefor in connection with a stand 4 attached to the fixed rail 1. The driving means for the said spindle and driver-roll has been omitted from the drawings.

Fig. 1 shows a cone-shaped shell 5 fitted upon a conical holder 6, and with such shell and its holder resting upon the driver-roll 2 in readiness to receive the load of yarn, thread, or the like, which is to be wound thereon. The holder is shown provided with an arbor or spindle 7 which at its inner rear end enters the bearing 8 provided in connection with a movable carrier 9 moving up and down upon an inclined guide

10. By the tendency of the carrier, arbor or spindle, and holder to gravitate toward the driver-roll, the surface of the shell, or that of the wound mass thereon, is kept pressed in driving contact with that of the 70 driver-roll, as will be understood. At 11 is shown a winding-guide, adjacent the driver-roll, such guide being mounted to slide longitudinally upon a supporting-rod 12 extending parallel with the driver-roll, 75 alongside the latter and supported by the stand 4, the said winding-guide having a long stem 13 which is connected pivotally, as at 14, with an arm 15 fixed upon the traverse rock-shaft 16 and extending upwardly therefrom. For the purpose of distributing the yarn, thread or the like in the desired helices or coils upon the shell in being wound thereon, the winding-guide is moved back and forth upon the said supporting rod, lengthwise of the driver-roll, 80 in this instance transversely of the machine as in prior machines of this class. Such movement of the winding-guide is caused by rocking movement transmitted to the 90 traverse rock-shaft 16 from the traverse mechanism which will now be described, and in which my invention resides, by means of the arm 17 fixed upon such rock-shaft and the connecting-rod 18 which is pivotally joined by one end thereof to the said arm the other end of such rod being connected to a member of the said traverse-mechanism.

The essential elements of the traverse-mechanism, proper, comprise the rotatable 100 actuator consisting of the movable arm 19 constituting a carrier for the wrist-pin 20 with which one end of connecting-rod 18, aforesaid, is pivotally engaged; the inner rotating crank comprising the crank-pin 21 105 with which the inner end of the said arm or wrist-pin-carrier 19 is pivotally engaged, and the disk 22 carrying the said crank-pin; and the outer rotating crank comprising the 110 crank-pin or pivot 23 entering a longitudinal groove 24 in the wrist-pin-carrier 19 so that the latter is free to slide as well as to swing or swivel upon the said crank-pin as upon a pivot, and the rotating disk 25 115 constituting a carrier for the said crank-pin or pivot 23. The crank-disk 22 is fast upon one end of a rotating shaft 26, and the crank-disk 25 is mounted concentrically with respect to the former, so as to rotate around the same center therewith, by being sleeved 120 upon the said shaft 26, the said crank-disk 25 being formed with a sleeve or extension 27 extending lengthwise of the shaft and fitting the latter. The parts are supported in working position by a pipe-bearing 28, 125 fixed upon the end-frame 1^a, and within which the sleeve 27 is fitted. The crank-disks 22 and 25 are operatively combined with one of the rotating shafts of the machine by connections acting to transmit mo- 130

tion from the latter thereto, causing them both to rotate at the same angular velocity but in opposite directions. Thus the sleeve 27 of the crank-disk 25 has fixed thereon a spur-gear 29 meshing with a spur-pinion 30 fixed upon the rotating shaft 31, so that the said crank-disk is caused to rotate oppositely with respect to the direction of rotation of the said shaft, and the shaft 26 of the crank-disk 22 has fixed thereon a spur-gear 32 meshing with a carrier spur-pinion 33 which in turn meshes with a spur-pinion 34 fixed on shaft 31, the spur-pinion 33 being employed to cause the said crank-disk to rotate in the same direction as the shaft 31, it following that the respective crank-disks are rotated oppositely with respect to each other. The crank-pin or pivot 23 is located at a greater radial distance from the center of rotation than the crank-pin 21.

In operation, the rotation of the crank-pin 21 and crank-pin 23 in opposite directions causes the inner end of wrist-pin-carrier 19 to be carried around in a circular path by the former crank-pin, such path being indicated by the dotted circles *a*, in Figs. 6 and 8, while the engagement of the other crank-pin with the body of the wrist-pin-carrier causes the latter to swing upon crank-pin 21, and at two opposite points in the rotation as the crank-pins pass each other the wrist-pin-carrier is caused to turn half-way around upon crank-pin 21, namely at the top and bottom of Figs. 6 and 8. The connection of wrist-pin-carrier 19 with crank-pin 21 causes the wrist-pin-carrier to move longitudinally upon crank-pin 23, in addition to rocking or swinging thereon. The result of the conjoint action of the parts is that the wrist-pin 20 is caused to pursue the elongated path or orbit previously mentioned. When the parts are proportioned substantially as in Figs. 1 and 2, the path or orbit of the wrist-pin is like that shown by the succession of small circles of the diagram in Fig. 6, such path crossing itself near each end, producing short terminal loops and a longer intermediate loop. The large circle *b* of Fig. 6 indicates the circle of revolution of the outer crank. The short radial lines indicate the distances that are passed over by the cranks in equal times. For one half of a rotation of the cranks the positions successively assumed by the wrist-pin carrier are indicated by lines *c*, *c*, etc., drawn from points on the small circle to the appropriate points on the large circle. To insure clearness in Fig. 6, these lines are omitted for the other half of the rotation. The motion of the wrist-pin as it follows the path or orbit shown by the succession of small circles is well adapted to the purpose of actuating the traverse-devices, *i. e.*, the devices by which the material being wound is conducted back and forth along the receivers on which it is

wound. When the diameter of the inner crank is equal to the radius of the outer crank as in Fig. 7, the path followed by the wrist-pin is like that shown in Fig. 8. In Figs. 6 and 8 the spaces between the short horizontal parallel lines which intersect the centers of the small circles representing the path of the wrist-pin indicate the distances which are traveled vertically by the wrist-pin in equal intervals of time. It will be perceived that in the case of both embodiments of the invention such distances are equal or approximately equal from close to one-reversing point of the traverse to close to the other, and that there is no material dwell or retardation adjacent such points.

My invention enables me to construct a crank-motion in which the wrist-pin travels in a narrow elongated path closely related to a straight line.

For the purpose of permitting the outer crank-pin or pivot I have in this instance, as before stated, provided the said outer crank-pin or pivot with an eccentric-mounting in connection with the rotating carrier thereof, such eccentric-mounting operating to cause the said crank-pin or pivot to change its position slightly with relation to its carrier. This eccentric mounting is constituted in the present embodiment of the invention by a journal 23^a with which the said crank-pin is furnished, fitting a bearing at 23^b which is provided in connection with the rotating carrier 25, the said journal and the crank-pin being eccentrically related to each other, as shown. To cause the eccentricity to act to produce the required change in the position of the crank-pin or pivot, a relative turning movement of journal and bearing is occasioned, such relative movement being either continuous or intermittent. The drawings show a convenient construction in which the journal has fixed thereon a spur-pinion 23^c meshing with a spur-pinion 23^d, of a different number of teeth, fixed upon the stationary pipe-bearing 28. As disk 25 rotates, carrying crank-pin 23 around, the engagement of spur-pinion 23^c with the fixed spur-pinion 23^d causes the crank-pin to make a partial rotation upon its own axis, shifting its position slightly, as aforesaid.

I claim as my invention:—

1. In combination, traverse-devices, traverse-mechanism comprising essentially an arm with which the said traverse-devices are connected, and two actuating cranks of different radii, rotating concentrically, the said arm being in sliding engagement with the crank of greater radius and bodily carried around by said crank in the rotation of the latter, and its inner end being in pivotal engagement with the crank of less radius and carried around thereby, and the arm being shifted lengthwise by such crank and

the point of connection of the traverse-devices being thereby given reciprocal movement within a narrow elongated path.

2. In combination, traverse-devices, and 5 traverse-mechanism comprising essentially two actuating cranks of different radii, rotating concentrically, an arm, and a wrist-pin carried by the said arm and operatively connected to the said traverse-devices, the 10 said arm in sliding engagement with the crank of greater radius and bodily carried around by said crank in the rotation of the latter, and its inner end being in pivotal engagement with the crank of less radius and 15 carried around thereby, the arm being shifted lengthwise by the latter crank and the wrist-pin being thereby given reciprocal movement within a narrow elongated path.

3. In combination, traverse-devices, a 20 wrist-pin carrier, a wrist-pin on the said carrier operatively connected with the said traverse-devices, two cranks rotating concentrically, of different radii, the said arm being in sliding engagement with the crank 25 of greater radius and bodily carried around by the latter in its rotation, and one end of the carrier being pivotally engaged with the crank of less radius and carried around thereby, the carrier being also shifted 30 lengthwise by such crank and the wrist-pin being given reciprocal movement in a narrow elongated path, and means for rotating said cranks continuously in opposite directions.

35 4. In combination, traverse-devices, a wrist-pin operatively connected with the said devices, a wrist-pin-carrier, a rotating crank with which the said wrist-pin-carrier is engaged, a second rotating crank with 40 which the said wrist-pin-carrier is in sliding as well as pivotal engagement, and devices for revolving said second crank around the same center as the first crank and permuting the same as it is revolved.

45 5. In combination, traverse-devices, a ro-

tatable actuator in operative connection with the said traverse-devices, a rotating crank with which the said actuator is engaged, a second rotating crank with which the said actuator is in sliding as well as 50 pivotal engagement, and devices for revolving said second crank about the same center as the first crank and permuting the same as it is revolved.

6. In combination, traverse-devices, a 55 wrist-pin connected operatively with the said devices, a wrist-pin-carrier, a rotating crank with which the said wrist-pin-carrier is engaged, a carrier rotating around the same center as the said crank, a pivot connecting the wrist-pin-carrier with the said rotating carrier and with which the wrist-pin-carrier is in sliding engagement, the 60 said pivot having an eccentric-mounting in connection with the rotating carrier, and 65 operating devices for the said pivot and its eccentric-mounting causing a permutation of the position of the pivot.

7. In combination, traverse-devices, a 70 wrist-pin connected operatively with the said devices, a wrist-pin-carrier, a rotating crank with which the said wrist-pin-carrier is engaged, a carrier rotating around the same center as the said crank, a pivot connecting the wrist-pin carrier with the said 75 rotating carrier and with which the wrist-pin carrier is in sliding engagement, the said pivot having a journal-portion mounted in the rotating carrier, such pivot and its journal-portion being eccentrically related, 80 and means for rotating said journal-portion in its bearing, the eccentricity causing a permutation of the pivot.

In testimony whereof I affix my signature in presence of two witnesses.

GEORGE W. FOSTER.
